UNITED STATES PATENT OFFICE.

WILLIAM E. ELLIOTT, OF GRAND RAPIDS, MICHIGAN.

HAND-TOOL FOR BUTTON-SETTING.

1,059,355.

Specification of Letters Patent.

Patented Apr. 22, 1913.

Application filed January 10, 1912. Serial No. 670,367.

To all whom it may concern:

Be it known that I, WILLIAM E. ELLIOTT, a citizen of the United States of America, residing at Grand Rapids, in the county of Kent and State of Michigan, have invented certain new and useful Improvements in Hand-Tools for Button-Setting; and I do hereby declare the following to be a full, clear, and exact description of the invention, such as will enable others skilled in the art to which it appertains to make and use the same.

My invention relates to improvements in hand tools for button setting and its object is to provide the same with improved means for holding the button and fastener, improved means for guiding and clenching the fastener and to provide the device with various new and useful features hereinafter more fully described and particularly pointed out in the claims reference being had to the accompanying drawings, in which:—

Figure 1 is a side elevation of a device embodying my invention; Fig. 2 a plan view of the same; Fig. 3 an elevation of the same with the handles broken away showing the side opposite to Fig. 1; Fig. 4 an end view of the same; Fig. 5 an inverted plan view showing the opposite side to that shown in Fig. 2; Fig. 6 a detail in side elevation showing the device open as it appears when in use; Fig. 7 a front end view of the same; Fig. 8 the same as Fig. 6 showing the same after the first clenching movement whereby the prongs of the fasteners are turned outward by the anvil; Fig. 9 the same as Fig. 8 in front elevation; Fig. 10 the device during the final clenching movement whereby the outer ends of the prongs of the fasteners are bent upward into the fabric by engagement with the end of the lower jaw; Fig. 11 a front view of the same as Fig. 10; Fig. 12 an inverted plan view of the upper jaw taken on the line 12—12 of Fig. 1 showing the staple guide; and Fig. 13 the same in side elevation.

Like numbers refer to like parts in all of the figures.

1 represents the upper jaw and 2 the lower jaw of the tool, pivoted to each other as at 3, the jaw 1 being provided with a lever or handle 1^a and the jaw 2 provided with a handle or lever 2^a.

4 is a spring which yieldingly holds the

handles separated to the limit and with the jaws spaced apart. The shoulders 5 engage and limit this opening movement.

6 is a leaf spring mounted on the top of the jaw 1 the end of the spring and the end of the jaw being superposed and recessed to receive the eye of the button and the crown of a staple shaped fastener 16. The button is placed on the top of the spring, the spring being held down in contact with the jaw by an arm 7 fixed on the lower jaw by means of screws or fasteners 14.

8 is an anvil slidable in the tubular end 9 of the lower jaw 2. This anvil has outwardly diverging recesses in the upper end to bend apart the ends of the fasteners as shown in Fig. 9. This anvil is supported upon an intermediately pivoted lever 10 mounted on the lower jaw as at 11, the forward end of said lever engaging a slot in the bottom of the anvil to keep the same from turning about its axis and supporting it normally in an elevated position. This lever is operated by means of a lug 12 projecting from the under side of the handle 1^a and having oppositely inclined faces to engage the lever and operate the same. The upper edge of the lever 10 where it engages the lug 12 is substantially concentric with the axis of the pivot 3 and slides on the surface of the lug until the angle of the lever passes the apex of the lug whereupon the lever is released and the end of the same slides along the oppositely inclined end of the lug.

13 is a finger guard on the lower handle 1^a to prevent pinching of the finger of the operator by the lever. To properly direct the fastener perpendicular to the fabric 17, to which the button is to be attached and the anvil 8, a pair of gripping members 18 is provided having notches in their adjacent edges properly located to receive the legs of the fastener 16 and direct the same. These grippers are pivoted to the under side of the upper jaw and are flexible or resilient as at 19 whereby they yieldingly grip the fastener and expand as occasion may require. A spring 20 is provided which tends to move the grippers away from the jaw 1 where they engage the fastener, and a shoulder 7^a on the arm 7 holds the grippers against said jaw when the jaws are in open position, and the grippers are limited in the movement away from the jaw.

1 by contact with a shoulder 1^b at the base of the jaw.

In operation, the button eye and the staple or fastener are inserted in the recess at the 5 end of the upper jaw 1 and spring 6 with the eye of the button between the grippers as in Fig. 6, the spring and grippers both being pressed close to the jaw by the arm 7 when the device is open. The fabric 17 to 10 which the button is to be attached is placed above the anvil in proper position and as the jaws begin to close the upper jaw moves away from the arm 7 thus releasing the spring which lifts the crown of the fastener up into the recess of the upper jaw and permits the gripper to move down upon the fastener and thus accurately adjust and properly direct it through the fabric and toward the anvil. As the ends of the fastener 15 penetrate the fabric and strike the anvil they are bent apart as the jaws close, the anvil being held up by the lever 10 engaging and sliding on the rearward inclined end of the lug 12. As the upper jaw reaches 20 the fabric, the angle of the lug 12 reaches the angle of the lever and slips off the end of the same. The anvil now descends in the tubular head 9 of the lower jaw and permits the ends of the fastener 16 to strike 25 the concave recesses 9^a in the head of the lower jaw and as the jaws are finally closed this head forces the ends of the fastener outward and upward still farther and well up into the fabric thus embedding the ends of 30 the fastener within the same in proper position to securely hold the button and avoid exposure of the ends of the fastener which latter would obviously be objectionable.

The fastener is spread by the clenching 40 operation and the grippers are spread apart somewhat thereby and will further yield to permit removal of the tool to repeat the operation elsewhere.

What I claim is:—

45 1. A hand tool for button setting, comprising a pair of pivoted jaws, levers to manually operate the same, a spring to hold the jaws spaced apart, the said upper jaw being adapted to carry a button and staple 50 shaped fastener, an anvil slidably mounted in the lower jaw and having diverging surfaces to bend apart the ends of the fastener, a pivoted lever mounted on the lower jaw and supporting the anvil, and a lug fixed 55 on the upper jaw engaging the lever to hold the anvil in raised position and adapted to automatically release the lever before the jaws are fully closed.

60 2. A hand tool for button setting, comprising an upper jaw and a lower jaw pivoted to each other, levers to manually operate the same, a spring to yieldingly hold the jaws spaced apart, the upper jaw being adapted to carry a button and a staple 65 shaped fastener, the lower jaw having a

tubular end opposite the end of the upper jaw, an anvil slidable in the said tubular end and having diverging recesses to bend apart the ends of the fastener, the end of the lower jaw also having outwardly and upwardly turned grooves to further bend the ends of the fastener, a lever intermediately pivoted on the lower jaw and supporting the anvil at its outer end, and a lug fixed in the lever of the upper jaw and having an inclined surface slidably engaging the lever to support the anvil and an oppositely inclined surface to slide on the end of the lever and release the anvil whereby the latter moves downward and permits the fastener to engage the tubular end of the lower jaw.

3. A hand tool for button setting, comprising an upper jaw and a lower jaw pivoted to each other, levers to manually operate the jaws, a spring mounted on the upper jaw, said jaw and spring being recessed to receive the eye of a button and a staple shaped fastener, an arm fixed on the lower jaw to engage and depress the spring, an anvil slidable in the outer end of the lower jaw and having diverging recesses, the end of the lower jaw also having outwardly and upwardly inclined recesses opposite the recesses in the anvil, a lever pivoted on the lower jaw and supporting the anvil at its outer end, and a lug on the lever of the upper jaw slidably engaging the other end of the anvil supporting lever to support the anvil and adapted to move beyond the end of the lever to release the anvil.

4. In combination with a button setting tool having an upper jaw adapted to carry a button and a fastener, and a lower jaw carrying means for clenching the fastener, a fastener guide pivoted between said jaws having yieldable portions constantly between said jaws to embrace the fastener and guide the same and to spread apart to release the fastener.

5. A button setting tool comprising an upper jaw adapted to carry a button and fastener, a lower jaw carrying means for clenching the fastener by bending the prongs of the same apart, and a divided and resilient plate pivoted between the jaws embracing the fastener and yielding apart as the fastener is clenched and to release the fastener after it has been clenched.

6. A button setting tool comprising an upper jaw adapted to carry a button and fastener, a lower jaw carrying means for clenching a fastener, and a pair of grippers consisting of a plate pivoted between said jaws to normally lie close to the upper jaw and moved away from the same toward the lower jaw when the jaws are moved toward each other, said plate being recessed in the

end to receive a button eye and a fastener and also longitudinally divided to yieldably separate when moved to embrace a fastener.

7. A button setting tool comprising an upper jaw adapted to carry a button and a fastener, a lower jaw carrying means for clutching a fastener, and a pair of grippers consisting of a plate pivoted to move between said jaws and to normally lie close to the upper jaw, said plate being longitudinally recessed in the end to receive the eye of a button and transversely recessed to re-

ceive a fastener, and also longitudinally divided and transversely yieldable to spread apart when moved to embrace a fastener, 15 and means for limiting the swinging movement of the plate between the jaws.

In testimony whereof I affix my signature in presence of two witnesses.

WILLIAM E. ELLIOTT.
